(57) CLAIM

We claim the ornamental design for the seating, as shown and described.

DESCRIPTION

FIG. 1 is a perspective view from the right side of the seating showing my new design;

FIG. 2 is a left-side perspective view thereof; and,

FIG. 3 is an end view thereof.

The broken lines in FIGS. 1-3 depict environment and form no part of the claim.

1 Claim, 3 Drawing Sheets
